UNITED STATES PATENT OFFICE.

CHARLES B. BATY, JR., AND FRANK E. GRAY, OF SACRAMENTO, CALIFORNIA; HANNAH F. GRAY ADMINISTRATRIX OF SAID FRANK E. GRAY, DECEASED; SAID GRAY ASSIGNOR TO SAID BATY.

TRANSFER MACHINE.

Application filed May 5, 1923. Serial No. 636,960.

To all whom it may concern:

Be it known that CHARLES B. BATY, Jr., and FRANK E. GRAY, citizens of the United States of America, residing at Sacramento, 5 in the county of Sacramento and State of California, have invented certain new and useful Improvements in Transfer Machines, of which the following is a specification.

This invention relates to improvements in 10 machines for printing and issuing transfers on street cars.

The object of the invention is to provide 15 a machine which may be manually set by a conductor to position certain type wheels, associated with means whereby type wheels 20 may be actuated to print on a strip selected data, and subsequently by actuating an operating knob, a transfer will be issued and a ribbon will be advanced for a subsequent 25 operation.

A further object of the invention is to 30 provide a bodily movable type carrying platform, resiliently mounted in a housing and adapted to be moved in printing relation by applied pressure to effect a printing 35 operation.

The invention also relates to improvements 40 in the details of construction and arrangement of parts which will be hereinafter described and particularly pointed 45 out in the claims.

In the drawings:

Fig. 1 is a side elevation of the improved 50 transfer machine.

Fig. 2 is a horizontal section substantially 55 on the line 2—2 of Fig. 1.

Fig. 3 is a section on the line 3—3 of 60 Fig. 1.

Fig. 4 is a detail section on the line 4—4 65 of Fig. 1.

Fig. 5 is a detail section on the line 5—5 70 of Fig. 1.

Fig. 6 is a detail view of one of the ribbon 75 rollers.

1 indicates a housing, which may be 80 inclosed in a suitable casing, the housing being provided with a front opening 2, a front transverse slit 3, and oppositely aligned longitudinal slits 4—4. A horizontal 85 partition or printing platen 5 is supported in the housing, and between the partition and one wall of the housing are four posts 6. Mounted to reciprocate on the 90 posts is a platform 7, and on the posts 95 between the partition 5 and the platform

are springs 8, which normally force or hold the platform against one wall of the housing. Extending from the platform and through a sleeve on the housing, is a stem 9, provided at its upper end with a flat knob 10, located to be conveniently depressed to 60 operate the machine.

The platform 7 is provided with an extension 11, and rising therefrom is a bracket 12, which aligns with similar brackets 13—13 65 also extending upwardly from the platform. Mounted in bearings formed in the brackets is a shaft 14, and on this shaft is a series of sleeves 15—16—17—18 and 19. On the inner end of each sleeve is a type wheel 20, 70 while on the outer end of each sleeve is a hand wheel 21, having peripheral flanges provided with numbers and letters to correspond to the numbers or letters on the type wheels. The face of each hand wheel 75 is provided with a series of openings or indentations 22 corresponding to the numbers and letters on the hand wheels, and cooperating with each hand wheel is a pawl 23 pivoted on the extension 11 and held in 80 operative relation by a spring 24, whereby to hold a selected type wheel in adjusted printing position.

Located in a frame 1^a extended from the 85 housing 1 is a magnifying glass 1^b so disposed with reference to the hand wheels as to magnify the characters on the peripheries of said wheels to readily permit the conductor to see the characters he desires to select in issuing a transfer.

Located in brackets extending from opposite sides of the housing are two shafts 25 and 26, which receive rollers 27 and 28. The roller 27 is provided at opposite ends with ratchet wheels 29, while the roller 28 90 is provided at one end with a single ratchet wheel 30. A spring actuated pawl 31 engages with one of the ratchet wheels 29 to prevent retrograde movement of the roller 27, while a similar pawl 32 engages 100 with the ratchet wheel 30 to prevent retrograde movement of roller 28.

A ribbon indicated at 34 is wound on the roller 28 and is fed step by step to the roller 27, as will presently appear. The ribbon 105 is located adjacent the partition or platen 5 and is normally in spaced relation to the type wheels, as shown.

Mounted in the housing beyond the partition 5 are two shafts 35 and 36. On the 110

shaft 35 is a ratchet wheel 37 held against retrograde movement by a spring pawl 38 and operated by a pawl 39, pivoted to the platform at 40, and held in operative relation with the ratchet wheel by a spring 41. The pawl 39 is provided with a series of teeth 42, which engage the teeth of the ratchet wheel to insure the requisite movement to feed the paper. Pivoted to the pawl 10 is a spring actuated pawl 43, which is positioned to engage one of the ratchet 75 verse slit 3 in the housing. Cooperating with end of the shaft 35 is a pinion 44, which meshes with a gear wheel 45 on the shaft 15 36. The gear wheel 45 also meshes with a pinion 46 on a shaft 47, carrying a paper feed roll 48, and located adjacent the transverse slit 3 in the housing. Cooperating with the paper feed roller 48 is an upper feed 20 roller 49, having a pinion 50 which meshes with the pinion 46, the two rollers acting to feed the paper from the machine.

51 indicates a stud having one end mounted in the housing, and fitting over 25 the opposite end is a lever 52 hinged at 53 and held in operative relation by a spring 54. A pair of washers are slipped on the stud 51 and between the same is a roll of 30 paper 55, the roll being engaged by a spring 35 pressed roller 56 to prevent it unwinding 100 too freely. The strip of paper passes from the roll and around a roller mounted in brackets on the partition 5, and is thence passed along the partition or platen and between the feed rolls 48 and 49.

Assume the roll of paper and the ribbon are in place and it is desired to issue a transfer. The hand wheels 21 are adjusted to bring the desired type to the bottom and 40 above the platen, then the operator exerts pressure on the flat knob 10 which moves the platform against the tension of the springs. This action moves the type wheels toward the ribbon and the imprint of the type is 45 made on the strip of paper and against the platen. Movement of the platform against the tension of the springs also actuates the pawl 39, and the saw-shaped teeth ride over the teeth of the ratchet wheel 37. Correspondingly the pawl 47 rides over the teeth 50 of the ratchet wheel 29, consequently in the printing movement of the platform, no motion is imparted to shaft 35 or the roller 27. Immediately pressure on the knob is 55 relieved, the springs automatically return the platform to normal position, hence the teeth 42 of the pawl 39 engage the teeth of the ratchet wheel 37, and partially rotates the latter, and the pawl 39 simultaneously 60 partially rotates the roller 27 and feeds the ribbon transversely across the type wheels, partial rotation of the ratchet wheel 37 rotates the gear 45 and through the gears 46 and 50, the paper feed rolls 48 and 49 are 65 rotated to feed the paper from the machine.

with the matter printed thereon by the type wheels, the feeding movement being such as to project the paper sufficient distance beyond the housing to include all the data printed thereon when torn off against the 70 walls of the slit.

The machine is designed to be set up in convenient reach of a conductor, so that when a transfer point is reached, the type 75 wheels can be quickly set and a transfer issued and torn off. The type wheels can be set by the conductor before the transfer point is reached so that as quickly as the knob can be depressed and the slips torn off, transfers can be issued without the usual 80 delays during rush hours.

Through the mechanism described, after a selection of type have been made, the 85 operation of printing is effected by pressure and in this movement the parts are set for a subsequent operation, that is, the feeding of the paper and feeding of the ribbon, this of course being accomplished by the action of the springs.

What we claim is:

1. In a machine of the class described, the combination with a housing, means for feeding a strip of paper through the housing, a reciprocally mounted platform mounted in the housing, a stem extending from the platform, a plurality of type wheels mounted on the platform, and springs to normally hold the type wheels spaced from the path of movement of the strip of paper, whereby when pressure is applied to the 95 stem and such pressure is removed the type wheels print on the paper and the paper feeding means is actuated.

2. In a machine of the class described, the combination of a housing, a platform 105 mounted in the housing, springs for normally forcing the platform toward one wall of the housing, a plurality of adjustable type wheels on the platform, means for individually adjusting the type wheels, a partition in the housing normally spaced from the type wheels, paper feeding mechanism, and means between the platform and the paper feeding mechanism for setting same 110 when the platform is forced against the tension of the springs to move the platform away from the wall of the housing, the springs acting to return the platform to normal position when pressure is relieved, the return movement of the platform causing actuation of the paper feeding mechanism.

3. In a machine of the class described, the combination of a housing, a platform therein, a stem extending from the platform and through the housing, a plurality of type 125 wheels carried by the platform, means for individually adjusting the type wheels, paper feeding mechanism, inking means for the type wheels, pressure on the stem causing movement of the platform and the type 130

wheels to print, and means for returning the platform to normal position and actuating the paper feeding mechanism and the inking means.

5 4. In a machine of the class described, the combination of a housing, a platform mounted for vertical movement in the housing, a stem extending from the platform and beyond the housing, a printing bed in 10 the housing, a shaft mounted on the platform, a plurality of telescopic sleeves on the shaft, a type wheel on one end of each shaft adjacent the printing bed, a hand wheel on the opposite end of each sleeve, 15 means for holding each hand wheel in adjusted position, springs for normally holding the type wheels away from the printing bed, paper feeding means, and inking means, pressure on the stem compressing 20 the springs and effecting a printing operation, return of the springs to normal position causing actuation of the paper feeding mechanism and the inking means.

5. In a machine of the class described, 25 the combination of a housing, a platform in the housing, a plurality of posts on which the platform is mounted, springs on the posts engaging the platform, a plurality of type wheels on the platform, a partition in 30 the housing beyond the type wheels, paper feeding rollers, and a pawl pivoted to the platform and positioned to be set by move-

ment of the platform in one direction to set the paper feeding mechanism, whereby when the platform is moved on the posts to 35 effect printing of the type against the partition the paper feeding mechanism will be set and upon return of the platform by the springs the paper feeding mechanism 40 will be operated.

6. In a machine of the class described, the combination of a housing, a platform movably mounted in the housing, a plurality of type wheels mounted on the platform, means outside the housing for adjusting and 45 holding the type wheels in adjusted position, a stem extending from the platform, a partition in the housing spaced from the type wheels, paper feeding rollers, gearing for operating the feeding rollers, a pawl 50 pivoted to the platform and engaging one of the gears, whereby when pressure is applied to the stem the platform will be moved to cause the type wheels to imprint against the partition and position the pawl for subsequent 55 operation of the feed rollers, and means for automatically returning the platform to normal position and simultaneously causing the pawl to actuate the feed mechanism.

In testimony whereof we affix our signatures.

CHARLES B. BATY, JR.
FRANK E. GRAY.
